FIG. 1. INVENTORS

August F. S. Osterberg
Hans G. Osterberg

UNITED STATES PATENT OFFICE.

AUGUST F. S. OSTERBERG AND HANS G. OSTERBERG, OF BOSTON,
MASSACHUSETTS.

PIANOFORTE-ACTION.

SPECIFICATION forming part of Letters Patent No. 498,523, dated May 30, 1893.

Application filed April 2, 1892. Serial No. 427,529. (No model.)

To all whom it may concern:

Be it known that we, AUGUST F. S. OSTERBERG and HANS G. OSTERBERG, of Boston, in the county of Suffolk and State of Massachusetts, have invented certain new and useful Improvements in Pianoforte-Actions, of which the following, taken in connection with the accompanying drawings, is a specification.

Our invention relates to improvements in the construction and arrangement of devices by which new and improved effects are produced in piano forte actions, especially in relation to "repeating" and to the action known as the sostenuto as well as to other divisions which will be best understood by reference to the drawings and specification.

Our improvements are illustrated in the accompanying drawings in which—

Figure 1 shows in end elevation the parts in which our invention is embodied. Fig. 2 shows most of the same parts enlarged so as to admit of more clearly showing the operation of the moving parts.

In the drawings, Fig. 1, A represents a piano key of ordinary construction, adapted to operate the sticker D through the following described mechanism in which B B' is the foot piece attached by a pivot to an extension part C, as shown. The lower end of the sticker D extends downward into a recess formed for it in the foot piece B B' in which it is free to slide up and down. Near the lower end of the sticker D, I have a bracket D', through which an adjusting screw D² works. This adjusting screw D² is so arranged as not to work longitudinally in the part D', but to work as a screw in the part B B', so that by turning this screw D² the sticker D may be adjusted as to its vertical relation with the key A. The upper end of the sticker D is pivoted at e, to the lever E, this lever E, being pivoted in turn to the flange T, which is made fast to the rail R. The outer end of this lever E, has attached to it a back-stop E². E' is a jack pivoted to the lever E at e'. This jack E' has a toe-piece E⁶ adapted to engage with the adjustable check-screw E⁷, so that as the jack is thrown up the toe-piece E⁶ coming in contact with the check E⁷ will cause the upper end of the jack E' to be thrown out from un-

der the shoulder E⁴ of the hammer butt E³, and thus allow the hammer to fall back. In addition to the shoulder E⁴ on the hammer-butt E³, we have a shoulder piece E⁵, the lower or working face of which is clearly above the working face of the shoulder E⁴. We call the shoulder E⁵ the "repeat" shoulder and it is on the end of the screw as shown, so that it may be adjustable. The object of this repeat shoulder E⁵ is to enable the player to make very rapid repetitions of the hammer-stroke, that is, the blows may be repeated without allowing the key to fall back to its resting position as is required in ordinary actions. Another improvement in connection with our hammer-butt consists in forming upon it a projecting angle H², adapted to engage with an adjustable buttress-piece J³, connected to the lower end of the damper lever J, so that as the hammer-butt (which swings on the pivot h in the flange T) swings, it will come in contact with the buttress J³ and throw the damper lever J back from the wire W, and allow it to sound. The damper levers J are pivoted at J' to projections made fast to the oscillating rail R' as shown, said oscillating rail R' having a longitudinal axis represented by R². As the rail, R' is oscillated, the projection r' impinges the damper levers, because the springs back of the damper heads force the lower ends of the damper levers back to the projection r', and then the dampers are removed from the string, since their levers must now move with the oscillating rail R'. 85

The oscillating rail R' may be turned by an ordinary lever attached to a pedal in the usual manner.

H is the hammer stem, attached to the butt E³, H' being the hammer, which when out of action is held in position by the hammer-stem rail R³. The jack E' is pressed forward by the spring e³, so that its upper end will always remain under the shoulders of the hammer-butt unless it is thrown out by the action of the toe-piece E⁶, as already described. 90

We will now describe our device for holding back any desired number of the dampers without holding them all back. This part of the action consists in forming at the lower end 100

of the damper lever J a point P, and in placing a little below it a pin S', there being one of these pins S' for each damper lever. These pins are set vertically in a moving rail S. This 5 moving rail S is adapted to have an upward motion when desired in the direction of the arrow (see Fig. 2), its motion being guided by the block K on the rail R. It is to be noticed that the moving rail S must not turn 10 on its axis, but must be moved upwardly and diagonally, always maintaining the pins S' in a vertical position. The action of this device is as follows: When the player desires to have certain notes sustained the required keys are depressed. This action will 15 throw the damper lever J forward so as to bring the point P to the position indicated by dotted lines at point P'. Now the moving rail S is thrown upward, and coming into such a 20 position that the pins S' will be behind the point P', and as the moving rail S is moved farther upward, it will cause the pins S' to carry the point P' forward so that the lower point of the damper lever J shall occupy the 25 position indicated by dotted lines at P², that is the damper lever will be thrown to the extreme position away from the wire, as indicated by dotted lines, and so long as the moving rail S is held up none of the dampers which 30 the player has selected to be held back will be allowed to fall from the wires. Thus all these selected notes will have their full open duration of tone. The object of moving the rail S, so as to force the point P' to the position P² is that during the period that the said 35 selected notes are held open the operator may want to put all the other wires in open vibration. It may be done in the usual manner by turning the oscillating rail R', that will cause 40 all of the damper levers to be removed from the wires. Those of the damper levers that were not previously held by the points S' will

occupy the middle position, that is, that indicated by the dotted lines at P'. 45

We claim—

1. In a hammer-butt of a piano-forte action, the combination of a normal shoulder E⁴ and an adjustable "repeat" shoulder E⁵, said shoulder E⁵ being distinct and separated from the normal shoulder E⁴, so that the jack E' having acted on the normal shoulder and given a full stroke of the hammer, may (before the hammer has time to return to its place of rest) be made to give a series of repeats on the "repeat" shoulder, without giving another full stroke: with the jack E', substantially as and for the purpose set forth. 50 55

2. In a piano forte action, a rail S, having vertical pins S', and adapted to move diagonally (but keeping the pins S' always vertical) in ways formed by the rail R and the blocks K, as described: with the rail R and blocks K, substantially as and for the purpose set forth. 60

3. In a piano forte action the combination 65 of the oscillating rail R, and located centrally in relation to the length of the damper levers J: with the diagonally moving rail S, and pins S', whereby the user may—while some of the damper levers are held back and the wires 70 kept in open vibration by the pins S', throw all of the other wires temporarily into open vibration, substantially as and for the purpose set forth. 75

In testimony whereof we have signed our names to this specification, in the presence of two subscribing witnesses, on this 21st day of March, A. D. 1892.

AUGUST F. S. OSTERBERG.
